UNITED STATES PATENT OFFICE,

THOMAS G. HAWKES, OF CORNING, NEW YORK.

DESIGN FOR THE ORNAMENTATION OF GLASSWARE.

SPECIFICATION forming part of Design No. 20,132, dated September 2, 1890.

Application filed August 7, 1890. Serial No. 361,397. Term of patent 14 years.

To all whom it may concern:

Be it known that I, THOMAS G. HAWKES, a citizen of the United States, residing at Corning, in the county of Steuben and State of New York, have invented and produced a new and original Design for the Ornamentation of Glass and other Ware, of which the following is a specification, reference being had to the accompanying drawings, forming part thereof, in which—

Figure I is a bottom plan view of a glass dish showing my design. Fig. II is a section on the line II II, Fig. I.

The leading features of my design consist in the paired or double bands crossed and extending across the article, forming pyramidal figures at their crossings, and an inner and an outer ring of quadrangular figures, fan-shaped figures, and angular lattice-work figures located in the inner quadrangular figures, rosette and angular figures in the outer quadrangular figures, and large fan-shaped figures between the outer ends of the bands.

1 are paired or double bands extending across the article represented and crossed by similar paired or double bands.

At the crossing of the bands pyramidal fig-

ures 2 are seen. The arrangement of these crossed, paired, or double bands produces an inner ring or series of quadrangular figures 30 and an outer ring or series of quadrangular figures.

3 are fan figures within the inner quadrangular figures, occupying a position between angular lattice-work figures 4, and representing rays, the lattice-work figures forming the arms of a partly-concealed Maltese cross. 35 5 are rosettes within the outer quadrangular figures, the space surrounding the rosettes being occupied by angular figures 6.

Large fan figures 7 extend around the edge or wall of the article between the outer ends of the paired or double bands.

Having thus described my invention, the following is what I claim as new therein and 45 desire to secure by Design Letters Patent:

The design for the ornamentation of glass and other ware, substantially as herein shown and described.

THOMAS G. HAWKES.
